UNITED STATES PATENT OFFICE.

ALBERT E. STIASNY, OF HOBOKEN, NEW JERSEY.

DESIGN FOR A SUPPORT FOR VASES, &c.

SPECIFICATION forming part of Design No. 23,968, dated January 29, 1895.

Application filed November 20, 1894. Serial No. 529,418. Term of patent 7 years.

To all whom it may concern:

Be it known that I, ALBERT E. STIASNY, a citizen of the United States, residing at Hoboken, in the county of Hudson and State of New Jersey, have invented a new and original Design for a Supporting-Plate for Vases and other Objects, of which the following is a specification, reference being had to the accompanying drawing, forming a part thereof, 10 the same being a perspective view of the design.

The leading feature of my design consists in the ornamentation by bear-like figures of the margin of an ornamental frame, such figures being in standing position, the upper portion of the body of each extending above the frame, while the same is supported by the fore-paws of each figure, and within the frame is supported a flat-plate. The bear-like figures 15 are arranged in standing position with their heads directed to one side; while by the

fore-paws of the same, the circular ornamental frame 2 is supported, within which frame is arranged a plate 3. The frame around the circumference of the plate 3 is provided at 25 its inner edge with a continuous series of inwardly-projecting angular scallops 4 at the bases of which is a groove or depression 5, which extends completely around the frame, said frame having outside of the groove or 30 depression, circular openings 6.

What I claim is—

The design for a support for vases and other objects, substantially as shown and described.

In testimony that I claim the foregoing as 35 my invention I have signed my name in presence of two subscribing witnesses.

ALBERT E. STIASNY.
